UNITED STATES PATENT OFFICE

2,269,732

SPRING CUSHION CONSTRUCTION

Otis Parker, Detroit, Mich., assignor to The Murray Corporation of America, Detroit, Mich., a corporation of Delaware

Application April 27, 1938, Serial No. 204,639

7 Claims. (Cl. 155—179)

The present invention relates to seat constructions of the type particularly adapted for automobiles.

While certain features of the present invention have general utility, the present invention is particularly adapted for seat cushion constructions in which the spring load supporting surface is formed of a plurality of specially formed sinuous spring elements extending substantially parallel to each other in a curved plane defining the load surface and secured at their ends to a frame.

One of the primary objects of the present invention is to provide an improved mounting means for a coil spring whereby the load, applied under normal use, is applied along substantially the longitudinal center line of the spring so that the coil spring is depressed without materially tilting the spring about its center line.

Another object of the invention is to provide an improved anchoring means for a coil spring.

Another object of the invention is to provide an improved and simplified spring seat construction whereby the applied load is more properly distributed over the entire seat construction.

Other objects of the invention will become apparent from the following specification, the drawing relating thereto, and from the claims herein-after set forth.

In the drawing, in which like numerals are used to designate like parts in the several views throughout:

Figure 1 is a cross-sectional view taken substantially along the line 1—1 of Fig. 2, showing a seat construction embodying features of the present invention;

Fig. 2 is a fragmentary, elevational view of the structure illustrated in Fig. 1; and

Fig. 3 is a fragmentary, enlarged perspective view of certain details of the structure illustrated in Figs. 1 and 2.

The present invention is illustrated as being applied to a seat back construction; and while the invention is particularly adapted to such a structure, it will be evident from the following description that the present invention has utility in other spring structures.

Referring to the drawing, a seat back construction is illustrated which comprises a generally rectangular base frame member 10 which may conveniently be formed of a section of wire or similar material. The base frame 10 has opposite end portions 11 and oppositely disposed side portions 12 and 14. The side portions 12 and 14 are formed with oppositely disposed, inwardly off-

set V-shaped supporting portions 16 at equal spaces therealong.

A helical coil spring 18 is disposed on and attached to each of the supporting portions 16 by means of an anchoring member, generally indicated at 20 in Fig. 3. The anchoring member 20 is preferably formed of a strip of wire which is bent at substantially its center to form a hook 22. The hook 22 passes under the base of the V-shaped supporting portion 16 and is then bent upwardly and downwardly to provide another hook portion 24 which is disposed over the lower convolution of the spring 18 at diametrically opposed points on the lower convolution. The free ends of the legs are then hooked under the lower convolution of the spring 18, as indicated at 26, so that the spring 18 is securely anchored to the supporting portion 16 of the back frame 10.

The opposite ends of the coil springs 18 serve to support a cushion, generally designated at 28; and are anchored to the cushion 28, according to the present invention, in a manner to be described in detail hereinafter. The cushion frame construction 28 is generally of the character and construction as disclosed and claimed in the pending application of Clarence H. Menge, Serial No. 139,765, filed April 29, 1937 now matured into Patent No. 2,175,062. The cushion frame 28 has the end edges thereof formed of sections of wire 30 and has the opposite side edges thereof formed of border channel elements 32 and 34. The end element 30 may conveniently be crimped into the channels in the members 32 and 34, as indicated at 36, and is preferably spaced slightly inwardly from the ends of the members 32 and 34.

The surface of the cushion 28 is composed of a plurality of arcuately disposed, continuously bent spring elements 38 of the general type disclosed in the Kaden Patent No. 2,000,399. As disclosed in this patent, the spring elements 38 are preferably formed of wire bent to provide a series of similar adjacent lateral convolutions all lying in substantially the same arcuate surface. After the spring wire has been bent to the predetermined desired form, the spring elements are normalized in order that they will have an inherent tendency to lie along arcs of substantially smaller radius than the arcs upon which they are disposed when utilized in the construction of a seat cushion.

These spring elements 38 are cut to suitable desired lengths and are severed at such a point that they provide a last lateral convolution extending substantially transversely of the length of the spring elements, which last lateral convo-

lution is utilized to anchor the ends of the spring elements in position in the border frame elements 32 and 34.

As disclosed in the Menge application above referred to, the border frame elements 32 and 34 are preferably formed of sheet metal of rolled sections which may conveniently be formed in continuous lengths. These border frame elements are generally of channel section with the walls of the channels crimped together at spaced points 39 therealong, thus providing channels which are adapted to receive and anchor the last lateral convolutions of the spring element 38 in position within the channel.

Since the spring elements making up the surface structure of the cushion construction are all tensioned to lie along arcs of substantially smaller radius than that on which they are disposed when mounted in the cushion construction, there is an inherent tendency to draw the border frame elements 32 and 34 together. Consequently, in order to brace the surface frame 20 against this support, it has been found necessary and desirable to provide suitable transverse frame elements 40. The elements 40 are preferably channel shaped with their ends 42 bent over the border frame elements 32 and 34. The bent over portions 42 may be welded, or otherwise suitably secured, to the border frame elements 32 and 34. The frame elements 40 are preferably arcuately disposed on an arc directed away from the arc of the elements 38 in order not to interfere with the function of the arcuately disposed sinusoidal spring element 38.

According to the present invention, in order to connect the spiral spring elements 18 to the cushion 28, the end convolutions 44 of the springs 18 are directed radially inwardly, as indicated at 46, and then upwardly at substantially the center of the spring, as indicated at 48. The free end 50 of the spring is again directed radially of the last convolution 44 in a plane substantially parallel to the plane of the portion 46. The portion 50 is adapted to be received within the channel formed in the bracing member 40 which is crimped together as indicated at 52 so that the end 50 of the spring 18 is securely anchored therein. The point at which the end 50 of the spring 18 is crimped to the brace 40 is at substantially the center of the spiral spring 18. Thus, under normal use, the force applied to the spring 18 is directed in a straight line along the longitudinal center line of the spring, so that there is no tendency for the spring 18 to be tilted as a load is applied thereto. The force is applied to the springs along a straight line which is substantially coincident with the longitudinal center lines of the springs so that the load is properly applied and distributed to the spring construction.

There is no interference between the connections for the spring elements 18 and the cushion 28 in the present structure, so that the spring surface formed by the element 38 is in no way interfered with by the remaining elements of the structure, thereby retaining the soft spring characteristics of this surface.

Formal changes may be made in the specific embodiment of the invention described without departing from the spirit and substance of the invention, the scope of which is commensurate with the appended claims.

What is claimed is:

1. A spring cushion construction comprising

a base frame, a border frame disposed in spaced relation to said base frame, spring elements connected to said border frame forming a spring load supporting surface, coil springs having an end extending on the diameters of the coils thereof and disposed between said base frame and said border frame, means connecting said coil springs to the base frame, and means connecting said end of the coil springs to the border frame, so that the load applied thereto is directed along substantially straight lines which are substantially coincident with the longitudinal center lines of the respective spiral springs.

2. A spring cushion construction comprising a base frame having a wire with a laterally extending portion, a border frame disposed in spaced relation to said base frame, spring elements connected to said border frame forming a spring load supporting surface, coil springs having an end extending on the diameters of the coils thereof and disposed between said base frame and said border frame, means connecting said coil springs solely to the laterally extending portion of said wire, and means connecting said ends of the coil springs to the border frame.

3. A spring cushion construction comprising a base frame, a border frame disposed in spaced relation to said base frame, spring elements connected to said border frame forming a spring load supporting surface, transversely extending brace members connected to said border frame and disposed in spaced relation to said spring elements, spiral springs interposed between said base frame and said border frame, means connecting said spiral springs to said base frame, and means connecting said spiral springs to said brace members, said last named means including a radially directed portion on each of said spiral springs which is attached to one of said brace members at substantially the center of said spiral spring.

4. A spring cushion construction comprising a base frame, a border frame disposed in spaced relation to said base frame, spring elements connected to said border frame forming a spring load supporting surface, transversely extending brace members of generally channel shape connected to said border frame and disposed in spaced relation to said spring elements, spiral springs interposed between said base frame and said border frame, means connecting said spiral springs to said base frame, and means connecting said spiral springs to said brace members, said last named means including radially directed spring end portions on each of said spiral springs, said end portions of each spring being received within the channel shaped brace members and crimped therein at substantially the center of each of said spiral springs so that the load applied thereto is directed along a substantially straight line which is substantially coincident with the longitudinal center line of the spiral spring.

5. In a spring cushion construction, a supporting frame having an offset curved supporting portion, a spiral spring supported on said offset portion, and means for anchoring said spiral spring to said curved portion, said last named means including a wire member which is bent intermediate its ends to form a hook, said hook being hooked under the base of said curved portion and then being bent to hook over the last convolution of said spiral spring adjacent said base, the free ends of said wire member

being then diverged outwardly and hooked under the curved portion and then passed upwardly and over the last convolution of the spring and hooked thereto at substantially diametrically opposed points.

6. A spring cushion construction comprising a generally rectangular base frame, the opposite sides of said base frame being shaped with oppositely disposed, inwardly directed offset spring supporting portions, a border frame disposed in spaced relation to said base frame, spring elements connected to said border frame forming a spring load supporting surface, spiral springs disposed between said base frame and said border frame, means connecting said spiral springs to the offset supporting portions of said base frame, and means connecting the spiral springs to the border frame, said last named connecting means engaging the spiral springs at substantially their respective centers so that the load applied thereto is directly along substantially straight lines which are substantially co-

incident with the longitudinal center lines of the respective spiral springs.

7. In a spring cushion construction, a supporting frame having a wire with a generally V-shaped offset supporting portion, another frame disposed in spaced relation to said first named frame, a spiral spring disposed between said frames, anchoring means securely anchoring one end of said spiral spring solely to said V-shaped portion of said wire, and means connecting the opposite end of said spiral spring to said second named frame, said last named connecting means including a radially directed spring end portion on said spiral spring and a member connected to said second named frame engaging said spring end portion at substantially the center of said spiral spring so that the load applied thereto is directed along a substantially straight line which is substantially coincident with the longitudinal center line of the spiral spring.
